UNITED STATES PATENT OFFICE.

HENRY F. W. SOHST, OF SAN FRANCISCO, CALIFORNIA.

PIPE-TONGS.

SPECIFICATION forming part of Letters Patent No. 331,456, dated December 1, 1885.

Application filed October 1, 1885. Serial No. 178,772. (No model.)

To all whom it may concern:

Be it known that I, HENRY F. W. SOHST, of the city and county of San Francisco, and State of California, have invented an Improvement in Pipe-Tongs; and I hereby declare the following to be a full, clear, and exact description thereof.

My invention relates to that class of pipe-tongs in which a fixed jaw is made integral with the stock or handle, and a swinging jaw is pivoted to the fixed jaw or to the stock; and my invention consists in the novel construction of the pivoted jaw, its arrangement with relation to the fixed jaw, and a spring 15 for the said pivoted jaw, all of which I shall hereinafter fully describe.

The object of my invention is to provide a simple and effective pipe-tongs adapted to receive different sizes of pipes and to grip 20 them without danger of slipping.

Referring to the accompanying drawings, Figure 1 is a perspective view of my pipe-tongs. Fig. 2 is an elevation showing the tongs when not in use.

25 A is a handle or stock, and B is the curved or hooked fixed jaw formed on one end of said stock.

C is the pivoted or swinging jaw. This is 30 longitudinally slotted, so that it has two separated side pieces, and these are united by a tie-piece, c. The face of this jaw is convexed and is preferably toothed, as shown. It is pivoted to the stock by the pin D, which is located at or near the point where the handle 35 or stock merges into the fixed jaw. The pivoted jaw is adapted to fit over the fixed jaw, its sides embracing said jaw until limited by the tie-piece c, bearing on the inner surface of said jaw. A spring, E, bearing on the tie-piece, holds the pivoted jaw normally to the 40 position just described. I provide the handle or stock A with a socketed extension, a, secured by a cross-pin, a'. This is intended to be used in case a greater leverage is needed. 45 The center of pivotal action of the jaw C is so located that the curve of the face of said jaw rapidly and positively moves past and back of the curve of the fixed jaw, thereby causing the jaw C to grip the pipe with certainty and 50 firmness, and by reason of fitting down over

the fixed jaw any size of pipe may be inserted. The spring renders the tongs easy of application, as it starts the jaw C to take hold immediately and holds it to its grip, all that is required being to hold the jaw back while fitting 55 the tongs on the pipe.

I am aware of the existence of tongs having a fixed and a pivoted jaw; but I am not aware that the pivoted jaw has ever been so slotted as to adapt it to fit over or embrace with its 60 entire length the fixed jaw.

Having thus described my invention, what I claim as new, and desire to secure by Letters Patent, is—

1. A pipe-tongs comprising a handle or 65 stock, a fixed curved or hooked jaw on said handle or stock, and a longitudinally-slotted or two-sided jaw having a convexed face and pivoted to the handle or stock, said jaw being adapted to fit down on each side of the fixed 70 jaw, substantially as described.

2. A pipe-tongs comprising a handle or stock, a fixed curved or hooked jaw on said handle or stock, a pivoted or swinging longitudinally-slotted or two-sided jaw having a 75 convexed face, and a tie-piece between the sides of said jaw to limit its movement over the fixed jaw, substantially as described.

3. A pipe-tongs comprising a handle or stock, a fixed curved or hooked jaw on said 80 handle or stock, a longitudinally-slotted or two-sided jaw having a convexed face and pivoted to the handle or stock, said jaw being adapted to fit down over the fixed jaw, and a spring bearing on the pivoted jaw, substantially 85 as described.

4. A pipe-tongs consisting of the handle or stock A, the fixed curved or hooked jaw B on its end, the longitudinally-slotted or two-sided convexed-faced jaw C, the pin D, pivoting said jaw to the handle or stock, the tie-piece c, between the sides of said jaw, and the spring E, bearing on the tie-piece, substantially 90 as described.

In witness whereof I have hereunto set my 95 hand.

HENRY F. W. SOHST.
